Howson & Howson

UNITED STATES PATENT OFFICE.

GEORGE BABE JACKSON, OF GUELPH, ONTARIO, CANADA.

TRACK-TORPEDO.

1,303,673.

Specification of Letters Patent. Patented May 13, 1919.

Application filed December 7, 1915. Serial No. 65,533.

To all whom it may concern:

Be it known that I, GEORGE B. JACKSON, a citizen of the United States, and a resident of Guelph, Province of Ontario, Dominion 5 of Canada, have invented certain Improvements in Track-Torpedoes, of which the following is a specification.

My invention relates to track torpedoes, more particularly torpedoes of the type set 10 forth in my Patent No. 1,182,767, dated May 9, 1916.

Torpedoes of this general type, designed to be held to the rail by securing straps of metal, are always in more or less danger of 15 being displaced, and in some instances have been brushed aside by the wheel of the engine instead of being detonated thereby.

The object of my invention is to provide means, readily attachable to track torpedoes, 20 that will prevent this condition; such means being preferably in the shape of a strap or band of metal which is carried by the body of the torpedo and provides a lug which lies in advance of the torpedo for initial engagement by the wheel of the engine whereby the torpedo will be maintained in position 25 until exploded by the crushing effect of the engine wheel.

Various ways of securing a lug-forming 30 strap to a torpedo may be employed, hence I do not wish to be limited to any particular arrangement.

These and other features of my invention are more fully described hereinafter, reference 35 being had to the accompanying drawings, in which:

Figure 1, is a perspective view of a torpedo in position upon the head of a rail, showing wheel-engaging lugs carried there- 40 by on opposite sides of the same;

Fig. 2, is an inverted plan view illustrating one manner of securing the lug-forming strap to the torpedo;

Fig. 3, is a plan view of a torpedo showing 45 another means of securing a lug-forming strap thereto;

Fig. 4, is a sectional view on the line IV—IV, Fig. 3;

Fig. 5, is an inverted plan view showing 50 a lug-forming strap of the single type and means for attaching the same to a torpedo;

Fig. 6, is a sectional view on the line VI—VI, Fig. 5;

Fig. 7, is a plan view, extended, of the lug- 55 forming strap shown in Figs. 5 and 6;

Fig. 8, is a perspective view of another lug-forming strap of the single type within the scope of my invention;

Fig. 9, is a plan view of the same as at- 60 tached to a torpedo;

Fig. 10, is an inverted plan view of a tor- 65 pedo showing a further modification of a lug-forming strap of the single type within the scope of my invention, attached thereto;

Fig. 11, is a sectional view on the line XI—XI, Fig. 10, and

Fig. 12, is a plan view, extended, of the lug-forming strap or band shown in Figs. 10 and 11.

In the drawings, 1 represents a rail head 70 to which a torpedo 2 having rail engaging ends 3 may be attached; such torpedo being of the usual detonating type.

In the structure shown in Fig. 1, I provide a lug-forming strap 4 of suitable metal, 75 which may be lead, which encircles the body of the torpedo, and in the present instance I have shown the said strap as secured to the body of the torpedo by twisting the same together as at 5; the independent ends 6 of 80 the strap being arranged to lie forward and back of the same upon the rail head and in the path of the advancing wheel. When such strap is in the form of lead or similar ductile metal, this method of securing the 85 same to the body of the torpedo may be em- ployed without difficulty.

In Figs. 3 and 4, I have shown another form of strap 4^a providing a double lug which may be secured to the torpedo in a 90 different manner, as by slitting the strap at 7 for the passage of the torpedo, which is frictionally retained in position by the looped portions 8 of the same. Fig. 4 shows the manner in which the loops pass around 95 the body of the torpedo; one or more of the loops being crimped adjacent the torpedo, as indicated at 9.

In Figs. 5, 6 and 7, I have shown a form of torpedo engaging strap 4^b having a single lug 6^b to be disposed in advance of the torpedo, which strap is held directly to the body of the torpedo by wrapping the same around such body and securing it thereto by bending over upon such strap side lugs 100 or extensions 10 which engage the edges of the strap, preferably on the under side of the torpedo. The strap, extended, is shown 105 in Fig. 7.

In Figs. 8 and 9, I have shown a further 110

modification of a lug-forming strap 4° made from a tubular section of ductile metal, preferably lead, which is split to provide torpedo engaging bands 11 and a single lug 6° 5 which may lie in advance of the torpedo for engagement by an engine wheel.

In Figs. 10, 11 and 12, I have shown another modification of a lug-forming strap 4° having a tongue 12 at one end and an 10 opening 13 in the body of the same to receive such tongue and through which the latter is passed after encircling the body of the 15 torpedo.

In all forms of my improved wheel-engaging lug, the same is carried by a strap attached directly to the body of the torpedo, either by wrapping it around the same and 20 securing it by a lug, tongue or the like, or by bands formed integrally with the strap, 25 or by wrapping the strap around the torpedo and securing it by twisting one part of the same with respect to the other.

When such lug and its securing means is 25 of ductile metal, such as lead, there is no danger of any of the parts flying or doing any damage when the torpedo is exploded.

I claim:

1. The combination with a track torpedo 30 of the self-contained, rail-engaging, type, of a wheel-engaging lug comprising a strip of metal for disposal in advance of the torpedo and having a portion thereof secured to and wholly embracing the body of the torpedo.

2. The combination with a track torpedo 35 of the self-contained, rail-engaging, type, of a wheel-engaging lug comprising a strip of ductile metal for disposal in advance of said

torpedo and having a portion confined to and encircling the body of the torpedo.

3. The combination with a track torpedo 40 of the self-contained, rail-engaging, type, of a wheel-engaging lug comprising a strip of ductile metal having one of its ends secured to and wholly embracing the body of the 45 torpedo.

4. The combination with a track torpedo 50 of the self-contained, rail-engaging, type, of a wheel-engaging lug comprising a strip of ductile metal having one end encircling the body of the torpedo, said lug being retained 55 with the torpedo by displacing a portion of the end encircling the torpedo with respect to the rest of the structure.

5. The combination with a track torpedo, 55 of a wheel-engaging lug comprising a strip of lead having one end secured to and wholly embracing the body of the torpedo and its opposite end projecting at one side of the 60 torpedo.

6. The combination with a track torpedo 65 of the self-contained, rail-engaging, type, of a strap or band wholly embracing the body of the torpedo, and a wheel-engaging lug integral with such strap or band and projecting at the side of the torpedo in advance 70 thereof.

7. The combination with a track torpedo 70 of the self-contained, rail-engaging, type, of a strap or band having one end tightly secured to and encircling the body of the torpedo and its opposite end forming a wheel-engaging lug projecting at one side of the 75 body of the torpedo.

GEORGE BABE JACKSON.
